CLAIM

The ornamental design for a housing for an arthropod trapping device, as shown and described.

DESCRIPTION

FIG. 1 is a front, right-side isometric view of an embodiment of a housing for an arthropod trapping device;

FIG. 2 is a rear, left-side isometric view of the housing for an arthropod trapping device of FIG. 1;

FIG. 3 is a front view of the housing for an arthropod trapping device of FIG. 1;

FIG. 4 is a right side view of the housing for an arthropod trapping device of FIG. 1;

FIG. 5 is a rear view of the housing for an arthropod trapping device of FIG. 1;

FIG. 6 is a left side view of the housing for an arthropod trapping device of FIG. 1;

FIG. 7 is a top view of the housing for an arthropod trapping device of FIG. 1; and,

FIG. 8 is a bottom view of the housing for an arthropod trapping device of FIG. 1.

The broken lines illustrate structure or features that form no part of the claimed design.

The dot-dash broken lines define the bounds of the claimed design and form no part thereof.

The drawings include shadows and reflections that indicate contour, not surface ornamentation.

Any patent application or patent to which this application claims benefit thereof, under 35 U.S.C. § 119(e), 120, or 121, is hereby incorporated herein by reference in its entirety.
